CLAIM

The ornamental design for an optimized split key ring separator, as shown and described.

DESCRIPTION

FIG. 1 is an isometric view of an optimized split key ring separator showing my new design;

FIG. 2 is a front elevation view thereof, the back side elevation being a mirror image;

FIG. 3 is a left side elevation view thereof, the right side elevation view being a mirror image;

FIG. 4 is a top plan view thereof; and,

FIG. 5 is a bottom plan view thereof.
